UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

BUCKET.

Application filed April 29, 1925. Serial No. 26,565.

This invention relates to new and useful improvements in buckets such as are commonly employed for loading, unloading, dredging, and similar work, and, more particularly, to improvements in the chain constructions covered by my former Patents, No. 889,170 of May 26, 1908, and No. 906,184 of December 8, 1908, respectively.

The object of this invention is to provide means to prevent the creeping of the chain on the hub of the power wheel, which has heretofore occurred when the chain is subjected to great stress in the closing of the bucket sections, and to more properly distribute the wear upon the various members of the chain.

In the clam-shell bucket of the power wheel type, such as the bucket which was the subject of Patent No. 906,184, of December 8, 1908, the closing of the bucket is effected by means of a power mechanism consisting of a large wheel located on the pivotal shaft which joins the two tray sections of the bucket together. Attached on either side of this large wheel are small hubs, and attached to these hubs and extending to the pivot at the top of the bucket to which the connecting arms are connected, are flat link chains. The closing rope, which is used for operating the bucket, is attached to the periphery of the large wheel just described, and its purpose is to rotate this wheel in the closing action of the bucket. The rotation of the wheel in turn causes the flat link chains to wind up upon the hubs, thus drawing the bucket sections together. The difference in the length of the lever arms represented by the distance between the center of the pivot shaft and the center of the closing rope on the outer edge of the power wheel as against the distance between the center of the pivot shaft and the center of the flat link chain as it lies upon the hub, is the mechanical means for gaining great power for forcing the bucket sections together. It has been found that the special flat link chains heretofore used and which were the subject of Patent No. 889,170, had a tendency to creep around the hubs, which were cylindrical in shape. Each of the links used in the chain was formed to lie upon the hub and to exactly match the contour of same. However, the great stress which it is forced to sustain during the closing of the bucket will have a tendency to draw the entire chain very closely around the hub, and the greater the wear en-

countered in the pin bearings, the greater was the tendency for the chain to creep and bind upon the surface of the hub, the binding, of course, coming from the great friction occurring during the creeping motion. The effect of all this was to gradually destroy the edges of the links and to tear out the holes in which the pins were inserted.

The object of this invention is to overcome this difficulty. In the new type of chain and hub arrangement, the hubs themselves are octagonal instead of round. Obviously, a greater surface for the chains to bear upon is thus provided. The links composing the chain have parallel or straight edges, and the chain is so proportioned that each set of links lies directly upon one of the flat surfaces of the hub and is held thereto. These flat surfaces tend to locate each section of the chain as it is wound up, independently of the section which had gone before, and overcomes all tendency for the chain to creep.

In the drawings, Figure 1 is a fragmentary end view of the power wheel and hub and chain attached thereto;

Figure 2 is a side view showing the chain wrapped around the same; and

Figure 3 is a view of the chain itself in front elevation.

Referring to the drawings in detail, 5 indicates the transverse shaft of a bucket of the type shown in my Patent No. 906,184, above referred to, to which are pivotally connected the bucket sections (not shown). Mounted upon the shaft 5 for rotation thereon is the power wheel 6, having a hub section on either side as indicated at 7. Each of said hub sections is provided with flat chain bearing surfaces as indicated at 8, and is also provided with projecting lugs 9, slotted as at 10 to receive the end links 11 of the chain 12, the end links 11 being pivotally connected to said lugs by transverse pins 13. The opposite ends of the chain 12 are connected to the pivot at the top of the bucket, where the connecting arms are attached.

The chain 12 consists of a single section A and a double section B, so constructed that when the sheave wheel has made one complete rotation in the closing of the bucket, the duplex section will wrap completely around the hub without such duplex section overlapping; that is to say, the duplex section of each chain is just long enough to encircle the hub to which it is attached, and the single

section, as the power wheel or sheave continues to rotate in the action of closing the bucket, will wrap on the hub in between the duplex section of the chain and without coming in contact with the latter section until the bucket is closed.

In the operation just described, it is obvious that the flat surfaces of the hub tend to locate each set of links as it is wound up, independently of the set which had gone before, and overcomes all tendency of the chain to creep. In the closing of the bucket, each set of links and pins thus performs its work somewhat independently of the links which have already been wound upon the hub, and this very materially cuts down the wear on both the links and the pins. The action of the new type of chain, as compared to the old, is analogous to the action of the chain around a sprocket wheel compared to a belt around a smooth pulley. In the first case there is very little slippage because each set of links is more or less positively engaged to the sprocket, while in the other case the belt operating upon a smooth surface does have a chance to slip.

While I have shown herein octagonal hubs connected to the power wheel, the number of flat chain bearing surfaces may be varied

by properly proportioning thereto the links 30 of the chain.

What I claim is:

1. In a bucket, a power wheel provided with a hub having a plurality of flat chain bearing surfaces. 35
2. In a bucket, a power wheel provided with a hub having a plurality of flat chain bearing surfaces, and a chain so proportioned that each set of links lies directly upon one of the flat surfaces of the hub. 40
3. In a bucket, a power wheel provided with a hub having a plurality of flat chain bearing surfaces, and a chain having a single section and a duplex section, each of said sections being adapted to make a single turn around the hub, and the links being so proportioned that each set of links lies directly upon one of the flat surfaces of the hub. 45
4. In a bucket, a rotatable power wheel provided with a hub presenting a plurality of angularly disposed flat surfaces, a lug projecting from said hub and disposed laterally with respect to said surfaces, and a chain having one end attached to said lug, each link thereof being proportioned to lie directly 50 upon one of said flat surfaces of said hub. 55

HERBERT S. ATKINSON.
